US0D1110671S

(12) **United States Design Patent** (10) **Patent No.:** **US D1,110,671 S**
(45) **Date of Patent:** ** *Feb. 3, 2026

(54) **PET TREAT**

(71) Applicant: **Spectrum Brands, Inc.**, Middleton, WI (US)

(72) Inventor: **Marc Kreamer**, Delray Beach, FL (US)

(73) Assignee: **Spectrum Brands, Inc.**, Middleton, WI (US)

(*) Notice: This patent is subject to a terminal disclaimer.

(**) Term: **15 Years**

(21) Appl. No.: **29/950,138**

(22) Filed: **Jul. 1, 2024**

Related U.S. Application Data

(60) Continuation of application No. 29/903,153, filed on Sep. 20, 2023, now abandoned, which is a continuation of application No. 29/833,598, filed on Apr. 5, 2022, now abandoned, which is a continuation of application No. 29/820,604, filed on Dec. 22, 2021, now Pat. No. Des. 948,163, which is a continuation of application No. 29/667,442, filed on Oct. 22, 2018, (Continued)

(57) **CLAIM**

The ornamental design for a pet treat as shown and described.

DESCRIPTION

FIG. 1 is a front, top, and left side perspective view of a pet treat according to the new design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The broken lines in the drawings illustrate portions of the pet treat that form no part of the claimed design.

1 Claim, 4 Drawing Sheets

Related U.S. Application Data

now Pat. No. Des. 942,117, which is a continuation of application No. 29/589,594, filed on Jan. 3, 2017, now Pat. No. Des. 831,297, which is a division of application No. 29/549,670, filed on Dec. 28, 2015, now Pat. No. Des. 781,525.
